STRIKING MECHANISM FOR CLOCKS

Joseph J. Claves, Detroit, Mich., assignor of one-third to Mrs. L. Hartrick and one-third to Arthur Wilson, both of Detroit, Mich.

Application June 5, 1936, Serial No. 83,614

2 Claims.

(Cl. 58—8)

This invention relates to clock mechanisms and more particularly to the striking mechanism thereof.

The primary object of the present invention is to provide a striking mechanism for use in combination with conventional clock mechanisms and embodying means for causing the clock to strike at predetermined intervals in a predetermined manner. More specifically, the present means functions at six A. M., twelve noon and six P. M. to operate a hammer to cause engagement thereof with a gong or other sound device a predetermined number of times, nine for example, with the successive strokes of the hammer at regularly timed intervals, and then after the completion of the nine strokes of the hammer to cause a second hammer to function in connection with a second gong or sound device having a different tone, there being a like number of strokes of the second hammer at a more rapid rate than those of the first hammer. At times other than those indicated the present mechanism functions to maintain the hammer actuating mechanism inoperative.

Another object of the invention is to provide a clock striking mechanism with means co-operating with the time train of a clock mechanism for accurately timing the actuation of the striking train, particularly in a device wherein the striking train functions at time intervals greater than one hour.

With the above and other ends in view the invention consists in matters hereinafter set forth with reference to the accompanying drawings, in which—

Figure 1 is an elevation of the present clock mechanism;

Fig. 2 is a section taken on the line 2—2 of Fig. 1;

Fig. 3 is a view taken substantially on the line 3—3 of Fig. 1, several of the parts illustrated in Fig. 1 being omitted from Fig. 3;

Figs. 4, 5, and 6 are fragmental elevations illustrating different stages of operation;

Fig. 7 is an elevation of the striking mechanism;

Fig. 8 is a plan of the striking mechanism;

Figs. 9 and 10 are opposite elevations of a detail, and

Fig. 11 is an elevation of a dial.

Like characters of reference are employed throughout to designate corresponding parts.

The numeral 1 designates the front plate and 2 the rear plate of the frame which supports the clock mechanism. Rotatably supported in

the plates 1 and 2 is a shaft 3 supporting the time train spring 4, the spring 4 being connected with a main gear 5 in the usual manner. The end 6 of the shaft 3 is squared or otherwise angularly formed for the reception of a key for winding the spring 4 and conventional means is provided for holding the spring in tension during and after being wound. The main gear 5 meshes with a pinion 7 on a shaft 8 carrying the gear 9, the latter being in constant mesh with a pinion 10 (shown only in Fig. 2). The pinion 10 is loosely mounted on an arbor 11 disposed centrally of the clock frame, there being a compressed coil spring 12 sleeved on the arbor and yieldably holding the pinion in engagement with a shoulder 13 on the arbor to establish a frictional driving connection therewith. The minute hand 14 is mounted on the outer end of the arbor 11.

The gear train between the arbor 11 and the spring 4 is controlled by a conventional escapement comprising a pallet member 15 pivoted on a shaft 16 and adapted for engagement with the teeth on the escape wheel 17. A pendulum (not shown) is connected with the shaft 16, in the usual manner, to control the movements of the pallet member. The escape wheel 17 is mounted upon a shaft 18 carrying a pinion 19 meshing with a gear 20. The gear 20 is mounted upon a shaft 21 carrying a pinion 22 meshing with a gear 23, the latter being mounted upon a shaft 24 having a pinion 25 meshing with the above described gear 9. Movement of the gear 9 is controlled by the above described escapement and gear train so that it functions to rotate the pinion 10 and arbor 11 at the rate of one complete revolution per hour.

Mounted upon the arbor 11, to rotate therewith, is a cam disk 26, the disk being circular in form with the exception of a single notch 27. The disk 26 is positioned with respect to the arbor 11 and the minute indicating hand thereon so that when the hand 14 is in a position pointing vertically (indicating the sixtieth minute) the notch 27 will be disposed at the top of the disk, substantially as shown in Fig. 4. The cam disk 26 has a pinion 28 formed integral therewith or connected thereto, the pinion being in mesh with a gear 29 rotatably supported upon a spindle 30 and having a pinion 31 connected thereto to rotate therewith and meshing with a gear 32. The gear 32 is loosely journaled upon the arbor 11 so that it may rotate freely with respect thereto and has a pinion 33 and a tubular extension 34 connected thereto, the tubular 35

extension 34 having the hour hand 35 mounted thereupon. The function of the gear train composed of gears 29 and 32 and pinions 28 and 31 is to reduce the speed of rotation of the tubular extension 34, with respect to the arbor 11, whereby the tubular extension 34 and pinion 33 make one complete revolution every twelve hours.

The above described structure, with the exception of the cam disk 26, comprises an example 10 of a conventional clock mechanism and forms no novel part of this invention. The mechanism to be hereinafter described constitutes the novel 15 part of the present clock, and it will be understood that its use is not confined to the particular mechanism above described. As will herein-after appear the present invention will function in combination with any clock mechanism wherein the time train embodies a part which makes one complete revolution every sixty minutes and a part which makes one complete revolution every twelve hours. Obviously, all clock mechanisms must necessarily include such parts.

Supported by the plate 1 is a rotatable shaft 36 having a gear 37 secured thereon and meshing 25 with the pinion 33. The gear 37 is of a diameter whereby it makes one half of a revolution with each revolution of the pinion 33, the result being that the shaft 36 makes one complete revolution every twenty-four hours. Mounted upon the 30 shaft 36 is a cam disk 38 having three notches 39, 40 and 41 formed in the periphery thereof. The notches are so disposed that the notches 39 and 40 are ninety degrees apart, the notches 40 and 41 ninety degrees apart, and the notches 41 and 35 38 one hundred and eighty degrees apart. The gear 37 and pinion 33 are relatively indexed whereby the notch 39 will be at the top of the disk 38, as shown in Fig. 4, when the hour hand 35 is in a position indicating six A. M., the notch 40 at the top when the hour hand 35 indicates twelve noon, and the notch 41 at the top when the hour hand 35 indicates six P. M.

Rotatably supported by the plates 1 and 2 is a shaft 42 supporting the striking train spring 43, the shaft having an angular end 44 for the reception 45 of a key or like instrument for winding the spring to place the same under tension. Connected with the spring 43 is a main gear 44 and means is illustrated at 45, on the main gear, for retaining the spring 43 in tension. The main gear 44 meshes with a pinion 46 on a shaft 47 having a gear 48 mounted thereon, the end of the shaft 47 being extended through the rear plate 2 as indicated at 49 for a purpose which will hereinafter appear. The gear 48 has a pin 50 secured 50 rigidly thereto on the side thereof which is nearest the front plate 1.

The gear 48 meshes with a pinion 51 on a shaft 52 carrying the gear 53. The gear 53 has a pin 54 secured to one of the faces thereof and projecting rigidly therefrom. Further, the gear 53 meshes with a pinion 55 on a shaft 56 having a gear 57 meshing with the pinion 53 which is on the shaft 59 supporting the vane type governor 60.

On the end 49 of the shaft 48 is mounted a wheel 61 having a series of pins 62 projecting perpendicular from one of the faces thereof. The pins 62 are equally spaced apart and are distributed over an arc of approximately one hundred 65 and eighty degrees, there preferably being nine of such pins. Diametrically opposite the series of pins 62 is a second series 63, on the opposite side of the wheel 61 and with the pins 63 closer together than the pins 62. Supported by the plate 2 are two hammers 64 and 65, the hammer 70

64 having an actuating part 66 disposed adjacent to the side of the wheel 61 carrying the pins 63 and the hammer 65 having an actuating part 67 disposed adjacent the side of the wheel 61 upon which the pins 62 are mounted. Upon rotation 5 of the wheel 61 the pins 63 engage the hammer actuator 66 and the pins 62 engage the hammer actuator 67. A bell, gong or other sound device is arranged adjacent each hammer, by way of example there being shown a bell 68 adjacent the hammer 64 and a bell 69 adjacent the hammer 65.

Pivottally mounted upon a spindle 70, carried by the plate 1, is a forked lever comprised of parts 71 and 72, these parts either being formed integral or otherwise connected together so that 15 they move in unison. The part 71 has an arm 73 extending inwardly therefrom across the cam disk 38 and with a reduced end portion 74 disposed in close proximity to the side of the gear 48 on which the pin 50 is mounted. The part 72 has an arm 20 or pin 75 extending across the cam disk 26. A spring 83 normally urges pivotal movement of the forked arm parts 71 and 72 to cause contact between the arms 73 and 75 and the cam disks 38 and 26 respectively.

Mounted in the plates 1 and 2 above the gear 53 is a shaft 76 having a lever 77 on the outer end thereof connected to the forked arm part 71 by a rigid link 78. Mounted upon the shaft 76 is a hook 79 disposed in close proximity to the gear 53 so that it is adapted to engage the pin 54 thereon.

Ordinarily, the mechanism as viewed in Fig. 1 is concealed by a dial 80, disposed as shown in Fig. 2 between the indicating hands 14 and 35 35 and the pinion 33. The dial, as shown in Fig. 11, has a central aperture 81 through which the arbor 11 and tubular extension 34 extend, and also apertures 82 providing access to the shafts 3 and 42. Instead of bearing the usual indicia, the present dial bears only the numerals "12" and "6".

In operation, when the two disks 26 and 38 have been moved to a position where the notch 27 is at the top of the disk 26 and one of the notches 39, 40 or 41 is at the top of the disk 38, the arm 75 falls into the notch 27 and the arm 73 into the notch in the disk 38. For example, as shown in Fig. 4 the arm 73 is shown in the notch 39. The movement of the forked arm part 71 accompanying such movement of the arms 73 and 75 pulls the link 78 downwardly, thereby rocking the lever 77 and shaft 76 to withdraw the hook 79 from engagement with the pin 54, thereby permitting the striking train to function. Upon functioning of the striking train the gear 48 makes approximately one complete revolution, that is, it moves from the position shown in Fig. 4 where the pin 50 is shown on the right hand side of the arm 73 until the pin strikes the left hand side of the reduced end 74 of said arm. When the pin 50 strikes the reduced end 74 of the arm 73 movement of the striking train is again stopped, although the hook 79 remains retracted so that it is out of the path of movement with the pin 54.

The gear 48, being connected to the shaft 47 65 causes the end 49 thereof to move approximately one complete revolution. During such movement, the wheel 61 in rotating therewith, causes the pins 63 to successively engage the actuator 66 and to thereby cause the hammer 64 to strike the bell 70 nine successive blows. After the completion of the above described nine strokes a slight pause ensues, after which the pins 62 engage the actuator 67 and cause the hammer 65 to strike the bell 69 nine successive times. Due to the fact 75

that the pins 62 are closer together than the pins 63 the second succession of hammer blows will be more rapid than the first.

With the parts in the position shown in Fig. 5 the striking train is held against movement. However, as the cam disks 26 and 38 continue to rotate with the time train they raise the forked arm parts 71 and 72 to their initial position, thus restoring the hook 79 to the path of movement 10 of the pin 54 and at the same time elevating the end 74 of the arm 73 from the path of movement of the pin 50 as shown in Fig. 6. The gear 48 then rotates a small fraction of a revolution during the rotation of the gear 53 necessary to cause 15 the pin 54 to again engage the hook 79. The mechanism is thus restored to its initial position and the same function will be repeated each time one of the notches 39, 40 or 41 and the notch 20 27 are at the top of their respective disks simultaneously.

Although a specific embodiment of the invention has been illustrated and described it will be understood that various changes may be made within the scope of the appended claims without 25 departing from the spirit of the invention, and such changes are contemplated.

What I claim is:

1. The combination with a clock having a time train with a minute shaft and an hour shaft, a 30 cam connected to the minute shaft, a second cam connected to the hour shaft by reducing gears providing a two to one speed reduction, said first cam having a single notch, said second cam having three notches arranged in a group with ninety 35 degrees between the adjacent notches of the group, a striking train including two gears each having a laterally projecting pin, a hook pivoted adjacent the first of said gears and adapted to engage the pin thereon to render the striking 40 train inoperative, a lever having parts thereon adapted to enter the notches in respective cams, means connecting said lever with said hook whereby movement of the lever incident to entrance of said parts into respective notches releases the hook from its respective pin and permits operation of the striking train, one of said 45 lever parts being positioned in the path of movement of the pin on the other of said gears by said lever movement whereby it renders the striking train inoperative again after approximately one revolution of said other gear, said other gear pin 50

and the lever part engaged thereby being relatively disposed whereby movement of the lever incident to removal of said parts from said notches releases the pin when the hook has been re-positioned in the path of the first mentioned pin.

2. The combination with a clock having a time train with a minute shaft and an hour shaft, a cam connected to the minute shaft, a second cam connected to the hour shaft by reducing gears 10 providing a two to one speed reduction, said first cam having a single notch, said second cam having three notches arranged in a group with ninety degrees between the adjacent notches of the group, a striking train including two gears each 15 having a laterally projecting pin, a hook pivoted adjacent the first of said gears and adapted to engage the pin thereon to render the striking train inoperative, a lever having parts thereon adapted to enter the notches in the respective 20 cams, means connecting said lever with said hook whereby movement of the lever incident to entrance of said parts into respective notches releases the hook from its respective pin and permits operation of the striking train, one of said 25 lever parts being positioned in the path of movement of the pin on the other of said gears by said lever movement whereby it renders the striking train inoperative again after approximately one revolution of the said other gear, said other 30 gear pin and the lever part engaged thereby being relatively disposed whereby movement of the lever incident to removal of said parts from said notches releases the pin when the hook has been repositioned in the path of the first mentioned pin, the pins on respective gears being disposed whereby upon release of the hook engaged pin the pin on the other gear is in a position whereby it cannot engage the lever part until said other gear has moved a few degrees less than one 35 complete revolution, and the pin on the second mentioned gear being positioned whereby it stops the gear train with the hook engaged pin substantially spaced from the hook, whereby upon release of the second mentioned pin the gear train 40 operates sufficiently to move the second mentioned pin past the plane of movement of the lever part which it engages.

JOSEPH J. CLAVES. 50
